UNITED STATES PATENT OFFICE.

LUDWIG MICHAELIS, OF BERLIN-WILMERSDORF, AND ERNST FERNHOLZ, OF BERLIN, GERMANY.

APPARATUS FOR SOLDERING, WELDING, AND THE LIKE.

1,096,837.

Specification of Letters Patent.

Patented May 12, 1914.

Application filed August 20, 1911. Serial No. 646,855.

To all whom it may concern:

Be it known that we, LUDWIG MICHAELIS and ERNST FERNHOLZ, citizens of the German Empire, and residents, respectively, of Berlin-Wilmersdorf and Berlin, both in the German Empire, have invented a new and useful Apparatus for Soldering, Welding, and the like, of which the following is a specification.

10 The subject-matter of this invention is apparatus for use with liquid combustibles for soldering, welding and the like.

Whereas it has for long been possible to operate with very various gaseous fuels, particularly acetylene and hydrogen, soldering, welding and similar burners which employ a combustible mixed with compressed oxygen or another gas which maintains combustion, recent attempts to use liquid fuels 20 for the same purpose have heretofore not led to practical results. Nevertheless liquid fuels are particularly suitable for this purpose, since the energy is highly concentrated in them, and as compared with gaseous fuels 25 they are handled much more readily and with less expense, because they can be conveyed everywhere in any desired vessels, while gaseous fuels can be conveyed only compressed in steel flasks.

30 The herein-described apparatus and the process of manipulating its burner obviate the manifold difficulties met with in using liquid fuels in blower burners.

One illustrative embodiment of the invention is represented by way of example in the accompanying drawings, wherein:—

Figure 1 is an elevation of the entire apparatus employed for working the burner, and Fig. 2 shows the burner alone on an enlarged scale. Fig. 3 is an enlarged side elevation, partly in section, of the top of the fuel vessel; and Fig. 4 is a fragmentary and sectional view of the burner vaporizer.

The apparatus comprises the steel flask 1 containing under pressure the gas for maintaining the combustion, *e. g.* air, air enriched with oxygen or pure oxygen, the portable fuel vessel 2 and the blow-pipe 3. The pressure reducing valve 4 is connected 45 to the steel flask 1, and the gas pipe 5 from this valve has two branches 6 and 7. The gas flowing through the branch 7 can be throttled by a throttling valve 8. A tube 9 connected to the branch 7 and a thin, flexible metallic pipe 10 connected to the branch 6 and coiled about the tube 9 lead to the head

11 of the vessel 2. This head 11 has three bores, see Fig. 3, to wit the bore 12 connected to the pipe 10 and continued at right angles into the vessel 2; the bore 13 connected to the tube 9 and continued without connection with the interior of the vessel 2 to a second tube 14, and the third bore 15 which connects a vertical pipe 16 extending to the bottom of the vessel 2 with a conduit 17, comprising two thin flexible metallic tubes, coiled about the tube 14. The bores 12 and 15 can be closed by valves 18 and 19, respectively.

The conduit 17 leads to the fuel pipe 20 of 70 the burner, to which the vaporizer 21 consisting of a plurality of turns of the pipe is connected. A part of the burner pipe 20 and the greater part of the vaporizer 21 are filled with a porous, incombustible material 75 as shown in Fig. 4. The part of the vaporizer nearest the burner, however, is unfilled. The vaporizer is so arranged that the pipe 20 opens into it at the part which is farthest removed from the vaporizing 80 flame.

Connected to the vaporizer is a pipe 22 whose one branch 23 leads to the vaporizer burner, while its second branch 25 leads behind the valve 26, interpolated in the pipe 22, to the pipe 27 for the gas maintaining 85 the combustion. This pipe 27 is connected to the tube 14. The vaporizer burner 24 is a Bunsen burner. The opening of its nozzle 28 can be regulated by the needle 29 by 90 means of the grip 30. The upper part 31 of the pipe 27 is bent and carries the mouthpiece 32 of the burner. To each burner belongs a series of exchangeable mouthpieces 32 of various bore.

95 The apparatus is manipulated as follows:—The reducing valve 4 is adjusted once for all so that the pressure at which it allows the gas to issue is equal to or a little higher than the maximum pressure 100 requisite for the blow pipe. As the valves 18 and 19 are always full open when the blow pipe is used, the same pressure consequently exists in the vessel 2. On the contrary, the pressure of the gas flowing to the 105 pipe 27 is adjusted by means of the throttle valve 8 to the suitable amount. In order to set the blow pipe in operation the vaporizer 21 is heated by any flame, and then all the valves 8, 18, 19, 26, and 29 are opened. 110 The vaporizer burner 24 and the main blow pipe 32 are then ignited. In order to adjust

the pressure of the fuel and gas to the mouthpiece 32 which is being used, the throttle valve 8 is adjusted as desired and the valve 26 gradually opened until an excess of 5 fuel is present which is known by the flame beginning to burn white. When the flame rises at this moment from the mouthpiece 32 and goes out, the gas pressure is correct and the throttle valve 8 correctly set. This 10 adjustment is readily effected by trial. When the correct gas pressure is ascertained the valve 26 is closed again a little to such an extent that the flame burns bluish green at the mouthpiece 32, whereby a powerfully 15 reducing action of the flame with the maximum attainable performance is indicated.

The fuel is vaporized in the coils of the vaporizer 21 filled with a porous mass, the said mass preventing unvaporized liquid 20 fuel issuing or the vaporization being irregular. The unfilled part of the vaporizer, which is highly heated in consequence of the proximity of the flame of the vaporizer burner and on account of the previous heating 25 of the fuel, acts as a superheater so that the fuel is completely dried in it and leaves it as gas.

We claim:—

1. In apparatus of the type described, the 30 combination of a vessel for gas under pressure for maintaining combustion, a blow pipe, a receptacle for liquid fuel, a gas pipe from the said vessel leading into the said receptacle, means for leading gas from the 35 said vessel to the said blow pipe, said blow pipe comprising a vaporizer and a burner for heating the vaporizer, and means for conducting fuel from said receptacle to said vaporizer and burner.

2. In apparatus of the type described, the 40 combination of a vessel for gas under pressure for maintaining combustion, a pressure reducing valve attached thereto, a blow pipe, a receptacle for liquid fuel, a gas 45 pipe leading from the said valve into the said receptacle, means for leading gas from the said valve to the said blow pipe, said blow pipe comprising a vaporizer and means for conducting fuel from said receptacle to 50 said vaporizer, and means for equalizing the pressure of the gas and vaporized fuel at the blow pipe.

3. In apparatus of the type described, the 55 combination of a vessel for gas under pressure for maintaining combustion, with a receptacle for liquid fuel, a blow pipe, a burner, a vaporizer communicating with the burner, said vaporizer consisting of a coiled pipe, a pipe connected to said receptacle and 60 opening into the said vaporizer at the part thereof farthest removed from the said burner, the said vaporizer being filled with the exception of the portion thereof located

nearest to the said burner with a suitable porous incombustible mass, a gas pipe leading from the vessel into said receptacle, means for leading the gas from said vessel to the blow pipe, and a pipe connecting the vaporizer with the blow pipe.

4. In apparatus of the type described, the 70 combination of a vessel for containing a gas under pressure for maintaining combustion, a blow pipe, a receptacle for liquid fuel, a gas pipe leading from said vessel into the receptacle, means for leading the gas 75 from the said receptacle to the said blow pipe, and a fuel pipe leading from the said receptacle to the blow pipe having a vaporizer interposed between said blow pipe and receptacle, said vaporizer comprising a 80 burner having a nozzle and a conical needle adjustable in said nozzle.

5. In apparatus of the type described, the 85 combination with a vessel for containing a gas under pressure for maintaining combustion, a receptacle for liquid fuel, a gas pipe from said vessel leading into the said receptacle, a blow pipe, means connected with the receptacle and with the vessel for supplying gas and fuel to the blow pipe, means 90 at the blow pipe for vaporizing the liquid fuel, and means for maintaining substantially the same pressure to the vaporized fuel as the gas maintaining the combustion.

6. In apparatus of the type described, 95 the combination of a vessel for gas under pressure for maintaining combustion, a blow pipe, a receptacle for liquid fuel, a gas pipe from the said vessel leading into the said receptacle, means for leading the gas from 100 the said vessel to the said blow pipe, a fuel pipe leading from the said receptacle to the said blow pipe and having a vaporizer interposed between said blow pipe and receptacle, and means for equalizing the pressure of the gas and vaporized fuel at the blow pipe.

7. In apparatus of the type described, the 110 combination of a vessel for gas under pressure for maintaining combustion, a blow pipe, a portable receptacle for liquid fuel, a flexible gas tube connecting the said vessel with the blow pipe and attached to the receptacle, a flexible gas pipe coiled about said tube and connecting the vessel with the receptacle, a vaporizer connected with the blow pipe, and a flexible fuel pipe coiled about the tube and connecting the vaporizer with the fuel receptacle.

In witness whereof we have hereunto set 120 our hands in presence of two witnesses.
